[57] CLAIM

The ornamental design for a bumper for personal watercraft, as shown and described.

DESCRIPTION

FIG. 1 is a right front perspective view of a bumper for personal watercraft showing my new design with strap portions being broken to permit maximum drawing scale;

FIG. 2 is a left rear perspective thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a reduced scale front elevation view to show proportional relationship of all elements thereof.
